ABSTRACT

Photographic film is reeled and a loop thereof is included between the payout reel and the takeup reel. A capstan engages the film in the loop and controls movement of the film past a beam recorder in accordance with the sprocket holes in the film. The capstan is controlled to cause the beam to record equispaced lines and sequential video frames are particularly positioned relative to the sprocket holes in the film. In one embodiment of the invention the loop is isolated by a sprocket wheel and a sprocket capstan engages the film in the loop. The speed of the sprocket wheel is controlled so that loop branches between it and the capstan have constant length to thereby indirectly couple the wheel and the capstan. A high inertia idler near the recording area suppresses high frequency vibrations in the film. In a second embodiment of the invention the smooth capstan is used in place of the sprocket and capstan. In a third embodiment of the invention, a pair of compliance arms are used to control servoing of the payout and takeup reels and a smooth capstan engages the film in the loop.

SYSTEM FOR CONTROLLING FILM MOTION

This application is a continuation of U.S. application Ser. No. 19,614, filed March 16, 1970, now abandoned; which is in turn a continuation-in-part of application Ser. No. 829,666, filed June 2, 1969, now abandoned.

The present invention relates to a system for controlling the advance of photographic film through the operating area of a beam recorder. Particularly, the invention relates to a film transport system cooperating with an electron beam for recording information directly on photographic film, in a line-for-line scanning pattern and arranged in sequential frames, the lines extending transverse to extension and motion of the film.

It is essential for this type of recording to match the positions of the video frames as recorded on the film to the positions of the sprocket holes thereof, as the positions of the sprocket holes determine the positioning of the film during reproduction. In addition, of course, the lines must be recorded to be completely straight and sequential lines must be equidistantly spaced. For several reasons, it is of particular advantage to control the recording process in such a manner that the film runs continuously and not intermittently. This mode of recording permits that the beam be deflected in one direction only, transverse to the direction of film motion. Intermittent recording in the respective standstill position of the film during recording each frame has the advantage that the accuracy of the control is exclusively a problem of electronics and does not depend on the constancy of physical motion. But the discontinuous process of recording has the disadvantage that the available period for moving and positioning the film during the vertical sync period is rather short, so that the film may still vibrate when recording has already begun.

The invention, therefore, relates particularly to film recording in which the film is moved continuously through an area where intersecting an electron beam, which is line-for-line deflected and intensity controlled, in a conventional manner, as far as TV technique is concerned, but which is not deflected in a vertical direction. It is presumed that the video signal controlling the electron gun is a manifestation of video signals on a complete frame basis, without interlacing of sequential fields.

The motion of a film at a constant speed, particularly during recording, poses various problems. For various reasons the film will tend to vibrate and oscillate, tending to cause the recording lines to appear jittery and variably spaced. In two of the embodiments of the invention, the film is moved by means of a sprocket wheel which is, of course, conventional for film transport. The advantage of sprockets is that slippage-free coupling relationship between sprocket wheel rotation and film advance is positively ensured. However, the film, as well as the sprocket wheel, tend to move irregularly due to external disturbances in the mechanical system. A particular source of such disturbances is the film feeding, reeling and rewinding mechanism, and the mechanical system which includes the sprocket drive must be expected to undergo irregular motions. Moreover, the sprockets of a sprocket wheel do not consistently enter accurately a film sprocket hole without scraping against the edges of the hole. Additionally, the motion has to be slaved to the vertical frame rate,

which means that for each vertical sync pulse period film has to be advanced for a particular distance, equivalent to a particular number of sprocket holes therein.

5 In accordance with a first embodiment of the invention, it is suggested to isolate a film loop of fixed length from the film feeding, reeling and takeup device. Within the loop the film is advanced by a sprocket capstan, and the average speed with which the film passes through the loop is indirectly controlled from the sprocket capstan. The sprocket capstan is narrow bandwidth position controlled for advancing the film in synchronism with the sequential frames of the video signal to be recorded and the sprocket holes in the film.

10 15 The sprocket capstan is broadband speed controlled to obtain straight and equidistantly spaced recording lines while maintaining the controlled position as between the video frames as a whole and the sprocket holes. A fine resolution tachometer disc bearing also markers representing the capstan sprockets is coupled to the sprocket capstan and its progressive position is compared with reference signals for speed controlling the sprocket capstan in a manner which also maintains or tends to maintain a fixed relation between the sprocket holes and the frame sequence.

20 25 The system, in accordance with the first embodiment of the invention, therefore, includes equipment for servoing the position of the sprocket capstan which directly moves the film past the recording area, whereby the progression of sprocket holes is slaved to the sequence of the vertical sync pulses to thereby establish a fixed position relationship between sequential frames and the sprocket hole pattern. A narrow-band control loop using the capstan markers establishes this control. 30 35 Broadband control using the high resolution disc pattern establishes smooth film advance for straight line recording without disturbing the position control either by directly coupling the two controls or by having them operate alternatively, using the fixed relationship of sprocket markers and high resolution pattern on the tachometer disc.

40 45 In addition, however, it must be observed that the tight fit as between several of the sprockets of the capstan and the corresponding number of sprocket holes in the film will cause the respective next sprocket to enter a sprocket hole to scrape along one or several edges of that hole, thereby setting up vibrations which are independent from the sprocket capstan and its speed. Therefore, high frequency motion of the film in the vicinity of the recording area is reduced or eliminated in two ways, one of which includes the broadband control.

50 55 First, the high resolution tachometer provides a sequence of relatively high frequency pulses, which are compared in phase and frequency with a sequence of pulses derived from the video signal. Any phase and/or frequency difference on a broadband basis will cause the sprocket capstan drive to change speed and relative phase position temporarily, and the resulting feedback loop operates in that the sprocket capstan is driven so as to maintain fixed phase relation between the tachometer pulses and the high frequency signals derived from the video signal.

60 65 In the preferred form of practicing the invention, the video frame position control compares the vertical sync pulses and the sprocket hole positions and the comparison is used to provide the reference signal for the

broadband speed control of the sprocket capstan. The motion of the sprocket capstan as represented by the high resolution tachometer pulses tracks variations in the frame sequence on a low frequency basis as the latter when undergoing changes will cause only low frequency (narrow bandwidth) changes in the reference signals operating on the broadband loop for fine speed control.

The second speed control of the tape takes care of momentary phase differences between the progressing video signal and sprocket capstan rotation not compensated by the control and resulting from the progressing engagement of sprockets with sprocket holes. A high-inertia idler is frictionally coupled to the film in the vicinity of the recording region and establishes nodes within the oscillation pattern set up in the film when the sprocket scrapes edges of the sprocket hole.

The film moves accurately where gripped by the sprocket capstan and in the immediate vicinity thereof, but the film reeling mechanism establishes irregularities, as stated. Therefore, the film as passing through the recording area is isolated from the film reeling mechanism in a manner which permits film advancing past the recording area in accordance with the accuracy of motion as provided by the sprocket capstan. For isolation of a portion of the film, use is made of a known expedient which comprises another sprocket wheel engaging the film in essentially two diametrically opposite locations to form a loop, whereby at any instant the amount of film fed into the loop equals the amount fed out of the loop. The sprocket capstan as well as the recording area operate the film within that loop.

As stated above, the sprocket wheel is indirectly coupled to the first sprocket, and particularly to the drive thereof, through a servo system. The servo system for the isolation sprocket wheel tends to maintain the amount of film constant between sprocket capstan and, for example, between the point where the film leaves the loop. As the total amount of film within the loop is constant at any instant by operation of the sprocket wheel itself, the control indirectly maintains also the amount of film between sprocket capstan and the loop entrance constant. The quantity of film extending between sprocket capstan and loop exit is monitored by a compliance arm operating also as a feeler. The film isolation sprocket wheel is speed controlled to maintain that arm in a particular position, thereby to maintain a particular quantity of film between loop exit and sprocket capstan and to thereby establish a rotational relationship between sprocket wheel and sprocket capstan, which is equivalent to a fixed coupling without, however, the disadvantage of any mechanical feedback effect of the sprocket wheel upon sprocket capstans as it would occur in the case the sprocket wheels were coupled by gearing and the like.

In a second embodiment of the invention, a smooth capstan is used in the loop to advance the film in place of the sprocket capstan of the first embodiment. In addition to the use of a smooth capstan, the second embodiment of the invention includes a direct monitoring of the sprocket holes of the film in the vicinity of the smooth capstan in place of the indirect monitoring of the sprocket holes by the use of the tachometer disc of the first embodiment of the invention.

A third embodiment of the invention includes the smooth capstan in the loop and the direct monitoring

of the sprocket holes in the vicinity of the smooth capstan and, in addition, eliminates the sprocket wheel and provides for a pair of compliance arms for use in directly servoing the payout and takeup reels.

5 While the specification concludes with claims particularly pointing out and distinctly claiming the subject matter which is regarded as the invention, it is believed that the invention, the objects and features of the invention and further objects, features and advantages thereof will be better understood with reference to the following description taken in connection with the accompanying drawings, in which:

FIG. 1 is a schematic view of a first embodiment of the invention;

10 FIG. 1a is a plan view of a detail particularly of the tachometer disc employed in the system shown in FIG. 1;

15 FIGS. 2 and 3 show details of the recording area respectively in sectional view in two orthogonal planes;

20 FIG. 4 is a modification of the system shown in FIG. 1;

25 FIG. 5 is a schematic view of a second embodiment of the invention; and

30 FIG. 6 is a schematic view of a third embodiment of the invention.

Proceeding now with the details of the description of the drawings, in FIG. 1 thereof there is illustrated a block diagram and partially a schematic construction view of the film advance and transport system, in accordance with the first embodiment of the present invention. There is shown a payout reel 10 for unexposed film 1, and a film takeup reel 11 receiving the exposed film. The payout reel 10 is mounted for free reeling, whereas reel 11 is driven by a motor 12 for tensioning of the film in advancing direction. The film must, of course, be maintained in a light-tight environment. Moreover, it is a principal aspect of the environment in which the invention is practiced that the film be transported and maintained in a low pressure region during operation so that a portion of the film can be brought in open contact with a near vacuum in which an electron beam is produced. Low pressure encapsulation is denoted schematically with reference numeral 2 in FIG. 1. The electron beam is produced inside of a casing 15' having an exit window 16 for the beam. The window 16 is open to the interior of encapsulation 2 but film 1 passes across that open window 16, and to some extent closes it. Thus, a high vacuum can readily be maintained in casing 15' by operation of a vacuum system 17. The pressure differential between chambers 2 and 15' operates for slight suction of the film against the window.

35 40 45 50 55 60 65

The electron gun in casing 15' is intensity controlled by operation of a video signal source 20 of conventional design; it can be any source—one can think of a remotely positioned TV camera—or source 20 could be a magnetic video tape which is currently being reproduced, etc.

Assuming that the video signal provided by source 20 is a composite one, then a sync separator 21 separate therefrom the horizontal and vertical sync pulses. The horizontal sync pulses control the horizontal deflection of the electron beam in system 15. There is no vertical deflection of the electron beam. The method employed in the system to be described is designed so that the tape runs continuously and the video signal is line-for-

line recorded by direct interaction of electrons of the electron beam with the photosensitive layer on the film. Furthermore, it is presumed that the video signal has a format that a frame is not divided into two interlaced fields. The various frames are separated on the film by a gap equivalent to the number of horizontal line periods which elapse between frames.

In order to provide the recording, the film has to be transported to pass window 16. The video lines must be recorded as straight lines and at an equidistant line spacing. For this, the film has to be transported at a very accurately constant rate of speed with as little temporary speed variations represented by high and medium frequency film vibrations as possible. Moreover, the recording should be made such that there is a fixed periodic position relation between the sprocket holes in the film and the recorded frames. For the sake of convenience, reference is made to a newer type of 16 mm. film with fairly wide spaced sprocket holes and in which there is one sprocket hole per frame. This, however, is not essential in principle for practicing the invention but facilitates explanation particularly of certain number relations.

Recording is carried out in a portion of film 1 which is mechanically isolated from payout reel 10, as well as from takeup reel 11. This isolation is provided in a manner known, per se, by means of a sprocket wheel 30 which can be regarded as an auxiliary film drive. The teeth of the sprocket wheel engage the sprocket holes of the film, whereby film from the payout reel 10 is gripped at region 31 by a few of the teeth of the sprocket wheel, passing into a loop 33 which includes the recording area and is gripped again by sprockets of wheel 30 in region 32 to be fed toward takeup reel 11. Inherently sprocket wheel 30 feeds precisely the same amount of film into loop 33 as it withdraws therefrom. Thus, between regions 31 and 32 there is always a definite length of film, regardless of the speed of wheel 30 equivalent of a fixed number of sprocket holes. The regions 31 and 32 can be defined, for example, more specifically as two oppositely located stationary points where the film is positively gripped by the sprocket wheel. Should there be, for any reason, a tendency to feed more film into the loop, more will be withdrawn as the loop is not capable by itself of storing more or less than a fixed amount of film given by the number of sprocket holes between point 31, along the film up to point 32. Complete isolation of the loop from the film storage arrangement 10-11 would seem to require forced constant speed of sprocket wheel 30. This, however, would not eliminate film speed irregularities within film loop 33. Therefore, the isolation is a controlled one in that sprocket wheel 30 is controlled in dependence upon conditions in the loop as they may vary due to controlled film speed in the vicinity of window 16. For this we turn first to the film drive system providing the required speed at window 16.

The film is pulled past the recording window 16 by operation of a capstan sprocket 40, which is driven by a motor 41. Motor 41 is a low inertia d-c motor. Speed control of motor 41 is one basic contributing factor for obtaining the object of the present invention, to ensure that the film passes the recording window 16 at a precise rate without flutter, so that straight and equidistantly spaced lines are recorded. Furthermore, for each complete video frame the film has to advance over a distance precisely equal to the distance between two

sprocket holes. The motion of the sprocket capstan 40, therefore, requires position and speed control interacting at least to the extent that position and speed control do not counteract. Sprocket capstan 40 and motor 41 are presumed to have a common shaft 42, or the equivalent for rotational synchronism. A tachometer disc 50 is coupled for positive rotation with sprocket capstan 40.

Essentially element 50 is a transparent disc bearing 10 contrast producing markers 51 along its periphery. The angular spacing of these markers is a precise duplication of the sprocket spacing on capstan 40, (it could be an integral multiple). For reasons of simplification it follows that there are as many markers 51 on tachometer disc 50 as there are sprockets on capstan 40, and both are as accurately distantly spaced as possible. The speed control for motor 41 is set up in such a manner that capstan 40 advances over an angle equal to sprocket and marker spacing during one video frame period.

To obtain straight and equidistantly spaced lines it is necessary to obtain accurate speed control on a broad-band basis, to eliminate higher frequency vibrations, i.e., film flutter, and the like. The tachometer 50 is, therefore, provided with a second track of equidistantly spaced markers 52 which are relatively large in number and represent the resolution of speed control. For practical purposes the number should be at least comparable with the number of lines per video frame; it can be the same number or even higher. There is, preferably, a fixed relation between the number of markers 52 and markers 51, i.e., the angle between any two sequential markers 51 is filled by the same number of markers 52. The motor 41 is now controlled so that the markers 52 pass a stationary point at frequency and phase tracking frequency and phase of a reference signal, and the reference signal bears a fixed relation to the frame rate.

40 The speed control for motor 41 is now provided as follows: The two marker tracks on tachometer disc 50 are scanned by photoelectric detectors, with markers 51 being scanned by detector 61 and markers 52 being scanned by detector 62. Detectors 63 and 64, respectively, denote output amplifiers for the two detectors 51 and the outputs, respectively, thereof operate toggle flip-flops 65 and 66. The output signals of toggle flip-flops 65 and 66 are, therefore, square waves. In particular, flip-flop 65 furnishes a low-frequency square wave of half the sprocket frequency. The output square wave as provided by flip-flop 66 is an integral multiple thereof, the factor being equal to number of markers 52 per spacing of markers 51. As stated, the factor may be in the order 10^2 or higher.

Sync separator 21 has an additional function, the separation of the vertical sync pulse from the composite video signal. This signal is presumed to operate a toggle flip-flop 22, therefore, providing a square wave output of half the vertical frame frequency. The outputs of toggle flip-flops 22 and 65 are fed to different inputs of a phase detector 70, preferably a phase detector adjusted for processing particularly square wave signals. Therefore, this phase detector 70 monitors the phase relationship between the frame repetition rate of the video signal, on one hand, and of the relative sprocket positions as represented by the output of flip-flop 65, on the other hand. The control provided the circuit to be described next is designed so that this phase detec-

tor provides a phase error "zero." Implementation may require that phase, error "zero" be defined by a 180° out-of-phase of the square waves provided by flip-flops 22 and 65, which relation has to do merely with the choice of the polarity of these signals.

A low bandpass filter 71 eliminates higher frequency components and ripples from the output of phase detector so that a slowly varying d-c or low frequency voltage is provided by filter 71 to a voltage controlled oscillator 72. VCO 72 is adjusted in that for an accurate phase relationship, i.e., for a phase error "zero," as defined, the frequency of VCO 72 is precisely the frequency which detector-amplifier channel 62-64 will furnish for precisely the desired instantaneous speed of the rotating system 41-40-50.

A toggle flip-flop 73 responds to the output of VCO 72 to reduce the frequency by the factor of two to establish a reference frequency with which to compare the output frequency of toggle flip-flop 66. The two flip-flops 66 and 73 now feed their outputs to a phase detector 74, as well as to a frequency discriminator 75, the outputs of which are fed to a summing point 76.

The frequency discriminator 75 has preferably threshold behavior, in that it provides a positive or a negative voltage of fixed amplitude to summing point 76 for clamping the output of phase detector 74 to that level. If flip-flops 73 and 66 provide signals of similar frequency but with an undesired phase shift in between, clamping is removed, and the phase detector output takes over to provide a signal proportional in amplitude and sign to the instantaneous phase error.

The output of summing point 76 is filtered by a filter 77 to remove switching ripples. The filter output signal is fed to a loop amplifier 78 which, in turn, feeds a driver amplifier 79, the output of which controls d-c motor 41. It can readily be seen that higher frequency vibrations in the film motion as noticeable near or at the capstan are controlled exclusively through the broadband feedback loop which derives its input to be controlled from the fine resolution marker track 52. The phase detector 70 will not, or hardly, respond to such vibrations but the detector system 74-75 will respond as toggle flip-flop 66 varies in phase and even rate, due to speed variations in the rotary drive system. Since the film is positively gripped by the sprocket wheel, there is an intimate and direct relationship between film vibrations and oscillations of the sprocket capstan and by speed controlling the latter, the film is pulled smoothly through the recording station.

The system is, of course, slaved to the frame rate as determined by the output pulses of sync separator 21, representing the vertical sync. The second loop superimposes the desired position relationship between sprocket holes, capstan sprockets and video frame rate. The reference signal for the speed control is varied to establish and maintain phase error "zero" between vertical sync pulses and sprocket representation. The position control is essentially operating only at the beginning, to "sync in" the system. Thereafter, a phase error will be detected by detector 70 only because of low frequency variations, either in the composite video signal or in the capstan or both. In essence, these will be accumulating residual errors from several high frequency oscillations wherein the fine speed control has reestablished phase synchronism but with a phase error of 360° or an integral multiple thereof as to the wave train of flip-flop 66.

The resulting speed change in the film by operation of the narrow band loop is a low frequency corrective which does not affect straightness of the video lines or spacing between adjacent pairs of lines. As the system is responsive to higher frequency control, the speed control loop through 52-64-66 tracks faithfully slow variations in the reference signal path 70-71-72-73 for the speed control and is set up so that the broadband loop establishes phase synchronism for the accurate position between the frames as a whole and the sprocket hole sequence.

As stated, the tachometer 50 is constructed so that there is a fixed and definite relationship between the number of markers 52 per angular distance between 15 sprocket marker 51 and a "normal" frequency is provided by VCO 72 for phase error "zero" in detector 70. It is thus apparent that the two controls for motor 41 provided in separate, but linked control loops, do not disturb each other and do not act against each other. 20 The fine speed control, operating to maintain the speed of the film so that the phase between the two pulse trains from toggle flip-flop 73 and 66 remains constant, inherently operates to maintain the sprocket position in synchronization with the vertical sync pulses. This does 25 not mean that the position control is superfluous, once synchronization between frames and sprockets is established, it merely means that the speed control, as provided by the fine resolution broadband loop cannot stabilize at a phase error "zero" as between immediate sequences of pulses from flip-flops 66 and 73, but the position control through detector 70, etc., ensures that there is no cumulative phase error and the square waves of 66 and 73 must return to synchronization always as if, on a wave-for-wave basis there was never a deviation.

For starting the film drive, a normal tachometer 43 monitors the film speed and through a control circuit 44 dominates the input of amplifier 79. As soon as the frequency discriminator 75 detects synchronism for the first time, the circuit 44 is turned off and the double loop takes over.

It will be observed that the control accurately positions progressive portions of the film in front of the recording slot or window 16, as the film is always positively engaged by the capstan sprocket 40. This includes that progressive sprocket holes in the film approaching capstan sprocket 40 are traversed respectively by a sprocket thereof in precise position for engagement. Nevertheless, the sprocket holes are never 45 that accurate so that there is sudden pushing and scraping as between an entering sprocket and edges of the respective sprocket hole. This tends to set up vibrations within the film. To the extent these vibrations affect the sprocket capstan, they are not removed by the control loops as described, but there are residual vibrations propagating toward the film portion facing window 16. Therefore, there is provided within the circuit, a high inertia idler 45 positioned in close proximity to recording window 16, and a pulley 46 resiliently mounted on a compliance arm 47 ensures a partial loop engagement of the film around idler 45. A positive and slippage-free engagement of the tensioned film against and with heavy idler 45 establishes a nodal area for the film where engaging the idler. Thus, nodes are set up in proximity of recording window 16 to prevent or at least 50 impede oscillating motion of the film increment interacting with the recording beam. The heavy idler limits 55 60 65

also the degree of oscillations film and capstan sprocket can undergo so that the amplitude of phase errors in the loop are kept down particularly for higher error frequencies. This in turn facilitates phase tracking by the motor control loops.

FIGS. 2 and 3 illustrate the recording area in greater detail. Wall portion 151 pertains to the housing electron gun 15 and has the aperture 16. Underneath there is a second slot 161, and the slight pressure differential on both sides of the wall 151 gently draws the film 1 flat towards recording window 16. The film edges rest against flat ledges 152 and 153 so that the emulsion, where to be exposed, is still free floating and does not engage the wall portions above and below recording slot 16. The heavy idler 45 is mounted in close proximity to the slot, sufficiently close so that the oscillation nodes in the film are as close to the slot 16 as possible. The idler should, however, be somewhat displaced from the slot in direction longitudinal to the film motion as well as normal to the plane of the film. Otherwise, the idler would have to mechanically urge film 1 toward slot 16, which is detrimental to the emulsion, even if there are ledges. Moreover, squeezing the film through such gap establishes itself a source of vibrations.

The compliance arm 47 with idler 46 establishes a variable length branch within film loop 33 between point 31, where the film leaves sprocket wheel 30 to enter loop 33 and sprocket capstan 40 which branch includes the recording area. Compliance arm 47 takes up any changes in the amount of film fed into film loop 33, i.e., arm 47 establishes a variable capacity temporary storage for a certain amount of film within loop 33. Of course, the amount of film within the loop 33 is precisely constant at any instant as the length of film between portions 31 and 32 is fixed. That means that in case more film than normal enters the film loop, more is withdrawn. However, capstan sprocket 40 as controlled enforces a precisely constant passage rate of film in its vicinity and in vicinity of the recording area so that the average speed of film within film loop 33 must equal the capstan speed. Thus, sprocket wheels 40 and 30 must be coupled to the extent that at least, on the average, the passage of film into and out of the loop is precisely equal to the controlled speed of sprocket capstan 40. The two sprocket wheels 30 and 40, however, must be coupled so that the former controls the latter without feedback, i.e., without having sprocket wheel 30 interfere with the controlled motion of capstan sprocket 40.

Elements 30 and 40 are coupled as follows: The amount of film in a second branch of film loop 33 as between capstan 40 and point 32 is monitored by a compliance arm acting as a feeler arm 80 with a pulley or the like 81. For a particular length of film between sprocket capstan 40 and point 32, compliance arm 80 has a particular position; if there is more or less film between capstan and point 32, arm 80 pivots in one or the opposite direction. A vane 82 or the like on arm 80 is deflected therewith to act as variable shutter in the light path of a photocell 83-lamp 84 arrangement monitoring the position of vane 82 and converts that variation in position into an electrical signal as developed in photodetector 83. The output of detector 83 controls an amplifier 85 which, in turn, controls a motor 86. Motor 86 drives sprocket wheel 30. The motor circuit may include a stabilizing loop, but the control in re-

sponse to position of arm 80 is also in a closed loop as speed changes in the motor 86 will cause more or less film to be drawn from the film loop branch between capstan 40 and point 32.

Generally the control operates so that motor 86 will increase the speed of sprocket wheel 30 in case capstan sprocket 40 feeds more film into loop branch 40-32 than sprocket wheel 30 takes out, and the speed control for motor 86 runs the opposite in case temporarily the film length between 40 and 32 declines. In essence, the sprocket wheel 30 is coupled to sprocket 40 as the control for motor 86 forces sprocket wheel and capstan to run in synchronism, whereby, however, the speed variations of wheel 30 are hardly fed back as speed disturbances for capstan 40. Any such disturbance should it occur, is, however, immediately corrected by the feedback control circuit for motor 41.

It follows that there remains complete isolation of loop 33 from irregularities in the tape reeling arrangement, which includes reels 10 and 11, by operation of sprocket wheel 30. The sprocket capstan 40 control, therefore, has to respond only to temporary higher frequency speed disturbances within the loop 33 and does not have to balance low frequency and large amplitude disturbances in film transportation as they may occur in the feed and takeup arrangement 10-11. Instead, the control for motor 86 in a follower-type control loop slaved to sprocket capstan 40 impedes or even inhibits these disturbances from propagating into the film loop 33. This loop has fixed film length by inherent operation of sprocket wheel 30 and the control of motor 86 establishes a constant loop branch 40-32. Loop branch 40-31 will thus be controlled indirectly to remain constant in length.

In summary, the system operates for positioning film in front of recording window 16 in strict phase synchronism with the video signal on a frame-for-frame basis for continuous recording of straight, equidistantly spaced lines. This result is obtained by combination of the narrow-band position control of the film in response to sequential passage of film areas destined to receive recording respectively of complete frames, by a broadband, high-frequency speed control, by a high inertia idler to eliminate higher frequency tape flutter, vibrations, etc., and by a film isolation loop indirectly coupled to the speed controlled sprocket capstan so that the average propagation rate of film through the loop precisely equals the average sprocket capstan speed.

It should be mentioned that the control circuit could be modified in that, for example, as illustrated in FIG. 4, the fine resolution track, as provided by the sequence of regularly spaced markers 52 on tach disc 50 has a spatial rate equivalent to the horizontal line frequencies, i.e., there are as many markers 52 per marker 51 as there are lines in a frame. The reference signals for the fine speed control will then be derived from sync separator 21 operating as input and providing for separated input signal to be fed via a toggle flip-flop 24 as a reference to the phase and frequency discriminator assembly 175, which includes the elements 74, 75 and 76. The output of discriminator assembly 175 is a d-c signal processed further by filter and loop amplifier 178 and fed to driver amplifier 79 via a switch 170. This establishes the normal operation for broadband speed control as described, slaving the film drive system line-for-line to the video signal.

For position control, particularly prior to normal operation, the output of phase detector 70 is used directly through an appropriate filter and amplifier circuit 177 for controlling driver amplifier 79 directly, so as to establish, on a narrow-band basis, a particular constant phase between the tachometer disc representing the capstan sprockets and the vertical sync pulses. For this control, switch 170 has the alternative position which is always established and maintained as long as phase detector 70 detects a position phase error. When such phase synchronism has been established, the output of phase detector 70 drops below the response threshold of switch control circuit 171 to change the position of switch 170 to the illustrated position, and the system proceeds from there.

It is important to note that as long as there is only a phase error in the broadband loop, there is inherently included a position control, because within the video signal has and maintains itself a fixed relationship between vertical and horizontal sync pulses. Thus, once the vertical sync pulses have established an initial fixed phase relationship between tach disc markers 51 and sprocket hole position, that phase can be maintained by considering horizontal sync pulses only. However, in case of broadband frequency error, the broadband loop may "sync in" the system to the "wrong" line sequence. This, however, is detected by phase detector 70 and switch 170 changes position to bring the control back into frame sprocket hole synchronism. Once the broadband loop has taken over again, synchronism between horizontal sync pulses and high resolution tachometer pulses is established for the correct association as between marker sequence and video lines.

FIG. 5 illustrates a second embodiment of the invention wherein a smooth capstan 200 is used to advance the film in the loop in place of the sprocket capstan 40 shown in FIG. 1. All elements of the second embodiment shown in FIG. 5 which are similar to elements shown in the first embodiments of FIG. 1 are given the same reference character. For example, the film 1 is pulled from the payout reel 10 using the sprocket wheel 30. The film 1 passes over the idler wheel 46 supported at the end of the compliance arm 47.

The film 1 is then directed to and taken from the capstan 200 through the use of the idler wheels 202 and 204. After passing over the idler wheel 204, the film then passes over the idler wheel 81 maintained at the end of the compliance arm 80. The compliance arm 80 is used as the control member in the servo system including the elements 82, 83 and 84 so as to produce a signal in accordance with the position of the compliance arm 80. The signal from the detector 83 is fed through the amplifier 85 to control the motor 86 which in turn drives the sprocket wheel 30. This servo system using the compliance arm 80 as the sensing element is substantially the same as that shown in the first embodiment of FIG. 1.

The takeup reel 11 is driven by the motor 12. The film 1 as it passes over the smooth capstan 200 is transported to pass by the window 16 in the electron gun 15.

In order to provide for the speed control of the motor 41 which drives the smooth capstan 200, the tachometer disc 50, which includes markers 52, is used, and the markers are sensed by the detector 62. This structure is substantially the same as the structure shown in the first embodiment of FIG. 1. However, in the second embodiment of FIG. 5, the tachometer disc only in-

cludes markers 52 and the low frequency signal is produced directly from the sprocket holes in the film 1 rather than the indirect system used in FIG. 1. This can be seen in FIG. 5 through the use of a light source 206 which produces light energy which is directed through the sprocket holes in the film 1 by the lens 208 which light energy impinges on photodetector 210. The output from the photodetector 210 is supplied to the amplifier 63 which is the same as the amplifier 63 of FIG. 1. The remaining elements of the speed control system are substantially identical to those shown in FIG. 1 and reference is made to the description of these elements under the description of the embodiment of FIG. 1.

The second embodiment of the invention shown in FIG. 5 therefore includes a smooth capstan to advance the film in the loop in place of the sprocket capstan. The use of the smooth capstan in place of the sprocket capstan eliminates the high frequency vibration caused by the sprockets entering and leaving the sprocket holes. This is referred to as sprocket tooth ripple, and such sprocket tooth ripple was eliminated in the first embodiment of the invention using the high-inertia idler. The second embodiment of the invention is therefore simpler in construction.

Another difference in the second embodiment of the invention as contrasted with the first embodiment of the invention is the detection of the low-frequency signal for the speed control directly from the film by monitoring the sprocket holes. This is contrasted with the use of a second track on the tachometer disc to provide an indirect detection of the sprocket holes of the embodiment of FIG. 1.

A third embodiment of the invention as shown in FIG. 6 includes further modifications relating to the film drive. Elements in the third embodiment of the invention which are similar to either of those shown in FIGS. 1 and 5 are given the same reference characters. In the third embodiment of the invention shown in FIG. 6, the film 1 is directly driven from the payout reel 10 to the takeup reel 11 and the sprocket wheel drive is eliminated. Specifically, in FIG. 6 the film as driven from the payout reel 10 passes over an idler roller 250. The film then continues around an idler roller 252 maintained at the end of a compliance arm 254. The film path then continues around idler roller 202, smooth capstan 200, idler roller 204 and around an idler roller 256, which is maintained at the end of a compliance arm 258. An idler roller 260 completes the path back to the takeup reel 11.

The compliance arms 254 and 258 are used to provide servoing of the motor drive for the payout reel 10 and takeup reel 11. Specifically, a vane element or the like 262 is coupled to the compliance arm 254 and acts as a variable shutter in the light path of a photocell 264 and light source 266. The position of the variable shutter 262 is monitored and converted into an electrical signal which is developed in the photodetector 264. The output of the detector 264 controls an amplifier 268 which in turn controls a motor 270 which drives the payout reel 10.

A similar arrangement including a variable vane 272, light source 274, a photodetector 276, and an amplifier 278 is used to provide a signal to control the motor 12 which drives the takeup reel 11.

This double compliance arm servoing of the payout and takeup reels provides for a substantially constant flow of film 1 and specifically a substantially constant

tension and film length in the film loop between the payout and takeup reels.

The smooth capstan 200 provides for a particular control of the film so that the recording of information is properly spaced relative to the sprocket holes and the motor drive and speed control for the smooth capstan 200 is essentially described with reference to the embodiments of the invention shown in FIGS. 1 through 6.

It is to be appreciated that other modifications of the invention can be made. For example, the film path past the window 16 may be as shown in application Ser. No. 691,492 filed Dec. 18, 1967, listing John W. Reeds, Jr., as the inventor and assigned to the same assignee as the instant application.

The invention is not limited to the embodiments described above, but all changes and modifications thereof not constituting departures from the spirit and scope of the invention are intended to be included.

We claim:

1. In a system for transporting through a recording area photographic film running from a payout reel to a takeup reel, the combination comprising:

first means including a sprocket wheel engaging the film for providing a film loop of fixed length between two points to obtain a feeding of film into the loop at one of the two points and out of the loop at the same rate at the other one of the two points;

second means including a capstan engaging the film inside of the loop for imparting motion upon the film, the second means further including means providing a closed loop servo responsive to the speed of the capstan to control the movement of the capstan to obtain a particular rate of progression of the film through the recording area within the loop; and

means including a second servo responsive to the instantaneous length of film between the capstan and a particular one of the two points and operatively coupled to the sprocket wheel for driving the sprocket wheel at a speed variable in accordance with variations in such instantaneous lengths of the film to control the speed of the film between the capstan and the particular point to maintain the length of the film between the capstan and the particular point substantially constant.

2. In a system for transporting through a recording area photographic film running from a payout reel to a takeup reel, the combination comprising:

first means including a sprocket wheel engaging the film for providing a film loop of fixed length between two points to obtain a feeding of film into the loop at one of the two points and out of the loop at the same rate at the other one of the two points;

second means including a capstan engaging the film inside of the loop for imparting motion upon the film, the second means further including means providing a closed loop servo to control the movement of the capstan to obtain a particular rate of progression of the film through the recording area within the loop;

means responsive to the instantaneous length of film between the capstan and a particular one of the two points and operatively coupled to the sprocket wheel for controlling the speed of the film between

the capstan and the particular point to maintain the length of the film between the capstan and the particular point substantially constant,

an idler of relatively high inertia for engaging the film in the vicinity of the recording area; and means tensioning the film against the idler to run in slippage-free frictional engagement with the film.

3. In a system as set forth in claim 2, the high inertia idler being positioned on the film in the branch of the loop extending between the capstan and the other one of the two points.

4. In a system for transporting through a recording area photographic film running from a payout reel to a takeup reel there being sprocket holes in the film and information being recorded in frames on the film and the frames being formed from successive lines of information, the combination comprising:

first means including a sprocket wheel engaging the film for providing a film loop of fixed length between two points to obtain a feeding of film into the loop at one of the two points and out of the loop at the same rate at the other one of the two points;

second means including a capstan engaging the film inside of the loop for imparting motion upon the film, the second means further including means providing a closed loop servo to control the movement of the capstan to obtain a particular rate of progression of the film through the recording area within the loop;

means including a second servo responsive to the instantaneous length of film between the capstan and a particular one of the two points and operatively coupled to the sprocket wheel for driving the sprocket wheel at a speed variable in accordance with variations in such instantaneous lengths of the film to control the speed of the film between the capstan and the particular point to maintain the length of the film between the capstan and the particular point substantially constant;

third means providing low frequency representation of progression and relative position of the sprocket holes within the loop to indicate the successive frames of information;

fourth means providing relatively high frequency representation of progression of the film within the loop to indicate the successive lines of information within each frame;

fifth means providing video signals including sync signals; and

sixth means included in the closed loop servo means in the second means and responsive to the sync signals and the representations provided by the third means and the fourth means for controlling the movement of the capstan.

5. In a system as set forth in claim 4, sixth means included within the closed loop servo means in the second means and responsive to the progression of the frames to be recorded on the film for comparing the representation thereof relative to the representation as provided by the third means to control the movements of the capstan in accordance with such comparison.

6. In a system as set forth in claim 5, the sixth means providing a reference signal varying in frequency with variations in the phase, the fifth means comparing the reference signal with the representation as provided by the fourth means to control the speed of the capstan so

as to obtain a particular relation between the compared signals.

7. In a system as set forth in claim 4, the second means including a low inertia member for driving the capstan, the system further including a relatively high inertia idler coupled to the film between the capstan and the other one of the points in the vicinity of the recording area.

8. In a system for recording video signals in sequential frames, each frame to be composed of a similar plurality of equidistantly spaced lines, on a photographic film by means of a beam of radiant energy, there being a supply reel and a takeup reel for the film, the combination comprising:

a sprocket capstan for engaging the sprocket holes in 15 the film to move the film past an area for interaction with the beam;

first means coupled to the capstan for driving the capstan and including means for providing first signals in representation of progression of capstan and 20 film, and second signals having particular relation to the first signals and provided in representation of progressing sprocket positions of the sprocket capstan;

second means including a source of reference signals 25 and responsive to the first signals and the reference signals to control the first means to obtain particular phase between first and reference signals; and

third means connected to be responsive to the progression of frames as represented in the video signals and further responsive to the second signals to obtain third signals in representation of the relative 30 positions of frames and sprocket holes in the film and connected to the second means to control the first means in response to the third signals to maintain a particular relation between recorded frames and sprocket holes.

9. In a system as set forth in claim 8, including a 40 sprocket wheel coupled to the film to isolate a fixed portion of the film from supply and takeup reels, the sprocket capstan engaging the film in the isolated portion, and means to control the sprocket wheel in response to progression of the sprocket capstan.

10. In a system as set forth in claim 8, including an 45 idler of relatively heavy mass frictionally and slippage-free coupled to the film in the vicinity of the recording area.

11. In a system as set forth in claim 8, the third means 50 controlling the first means and overriding the control as provided by the second means.

12. In a system as set forth in claim 8, the third means being connected to the second means in that the reference signals are derived from the third signals.

13. In a system as set forth in claim 8, there being 55 means to separate vertical synchronization pulses from the video signals, the first means including means rotating with the sprocket capstan to provide the second signals, the third means providing phase representation as between the vertical sync pulses and the second signals, the third signals controlling a voltage controlled oscillation serving as source of reference signals in the second means.

14. In a system as set forth in claim 8, there being 60 means to separate horizontal and vertical synchronization pulses from the video signals, the horizontal sync pulses serving as reference signals in the second means,

the vertical sync pulses being compared with the second signals in the third means to provide the third signals, and means to place the first means under control of the third or the second means, respectively, in response to absence or presence of the particular relation.

15. In a system for transporting photographic film past a region for recording thereon, the combination comprising:

a sprocket wheel for engaging the film in opposite points and establishing a constant length loop; a sprocket capstan for engaging the film in the loop to move the film through the region; means coupled to the sprocket wheel to control the motion of the sprocket wheel to maintain a particular film length between the capstan and the sprocket wheel; a low inertia motor for driving the capstan; a high inertia idler engaging the film in the loop and in the vicinity of the region; and means coupled to the film for tensioning the film in a partial loop against the high inertia idler.

16. In a system for transporting film having sprocket holes running from a payout reel to a takeup reel, the combination comprising:

first means for providing a film loop of fixed length between two points, feeding film into the loop at one of the two points and out of the loop at approximately the same rate at the other one of the two points;

second means including a capstan engaging the film inside of the loop for imparting motion upon the film, further including means to control the capstan in accordance with the rate of progression of the sprocket holes to obtain a particular rate of progression of the film through a particular area within the loop; and

third means responsive to the instantaneous length of film between the capstan and at least one of the points and coupled to the first means for maintaining the latter length substantially constant.

17. In a system as set forth in claim 16 wherein the first means includes a sprocket wheel engaging the sprocket holes of the film at the two points.

18. In a system as set forth in claim 16 wherein the first means includes drive means for the payout and takeup reels and the two points are the payout and takeup reels.

19. In a system as set forth in claim 16 wherein the second means includes fourth means providing representation of progression and relative position of the sprocket holes within the loop; and

fifth means also included in the second means for controlling the capstan in response to the representations provided by the fourth means.

20. In a system as set forth in claim 19 wherein the fourth means additionally provides relative high frequency representation of the progression of the film within the loop.

21. In a system for providing movement of a film having sprocket holes, there being a supply reel and a takeup reel for the film, the combination comprising:

a capstan for engaging the film to move the film past an area for interaction; first means for controlling the movement of the capstan and including means for providing first signals

- in representation of progression of the capstan and including means for providing second signals in representation of progressing sprocket holes of the film;
- second means including a source of reference signals and responsive to the second signals to compare the reference signals and the second signals to produce a third signal; and
- third means for comparing the first signals and the third signals to produce a fourth signal in accordance with such comparison and with the fourth signal providing a control of the first means for obtaining a particular phase between the second and reference signals and for producing a particular movement of the capstan.
22. In a system for transporting from a payout reel to a takeup reel film having sprocket holes and for recording video information on the film in successive frames and successive lines of information within each frame in accordance with video signals having sync signals, the combination comprising:
- first means for providing a film loop of fixed length;
  - second means including a capstan engaging the film at a particular position within the loop for imparting motion to the film;
  - third means responsive to the sprocket holes for providing a control signal representative of the progression and relative position of the sprocket holes;
  - fourth means including a first servo coupled to the second and third means and responsive to the control signal and the video sync signals for controlling the movements of the capstan in accordance with such comparison to obtain a particular rate of progression of the film within the loop; and
  - fifth means including a second servo responsive to the relative length of film at each instant between the particular position and the sprocket for driving the sprocket at a speed adjustable in accordance with such relative length of film at each instant to maintain such length of film substantially constant at each instant.
23. In a system as set forth in claim 22 wherein the third means provides for a direct monitoring of the sprocket holes in the film and the capstan is a sprocket capstan.
24. In a system as set forth in claim 22 wherein the third means provides for an indirect monitoring of the sprocket holes.
25. In a system for transporting film from a payout reel to a takeup reel,
- first means for engaging the film at a pair of spaced positions on the film to provide a loop of fixed length between the pair of spaced positions and for driving the film at the pair of spaced positions,
  - capstan means engaging the film at a particular position between the pair of spaced positions to drive the film,
  - first sensing means for sensing the movement of the film between a first one of the spaced positions and the capstan means to provide first control signals,
  - second sensing means for sensing the movement of the film between the capstan means and the other one of the spaced positions to provide second control signals,

- first servo means responsive to the first control signals for controlling the operation of the capstan means in driving the film between the pair of spaced positions, and
- second servo means responsive to the second control signals for controlling the operation of the first means in driving the film at the pair of spaced positions.
26. In the system set forth in claim 25, wherein means are included for providing video information to be recorded in successive frames and successive lines of information within each frame and for providing vertical sync signals defining the successive frames and wherein the first servo means are responsive to the vertical sync signals and the first control signals for comparing such signals to control the operation of the capstan means in accordance with such comparison and wherein means are disposed near the capstan for recording the video information on the film.
27. In the system set forth in claim 26, a high inertia idler engaging the film at a position between the first one of the spaced positions and the capstan means to impede oscillations of the film between the first one of the spaced positions and the capstan means.
28. In the system set forth in claim 26, the film having sprocket holes,
- the first sensing means including means for producing the first control signals in accordance with the movements of the sprocket holes on the film past the capstan means and for producing third control signals in accordance with incremental movements of the film past the capstan means in the intervals between the successive sprocket holes,
  - the first servo means including means for producing signals of a variable frequency in accordance with the comparison between the vertical sync signals and the first control signals,
  - the first servo means also including means responsive to the third control signals and the signals of variable frequency for comparing such signals to control the operation of the capstan means in accordance with such comparison.
29. In the system set forth in claim 28, the recording means being disposed at a position between the first one of the spaced positions and the capstan means and a high inertia idler being disposed between the first one of the spaced positions and the recording means to impede oscillations of the film during the movement of the film past the recording means.
30. In a system for transporting through a recording area photographic film running from a payout reel to a takeup reel, the combination comprising:
- first means including a sprocket wheel engaging the film for providing a film loop of fixed length between two points to obtain a feeding of the film into the loop at one of the two points and out of the loop at the same rate at the other one of the two points,
  - second means including a capstan engaging the film inside of the loop for imparting motion to the film,
  - third means disposed between the capstan and one of the two points for sensing the tension of the film

between the capstan and the one of the two points to produce a signal representing such tension, fourth means operatively coupled to the sprocket wheel for driving the sprocket wheel, and fifth means responsive to the signal representing the tension of the film and operatively coupled to the fourth means for controlling the operation of the fourth means in driving the sprocket wheel in accordance with the characteristics of the signal.

31. In a system as set forth in claim 30, means disposed between the capstan and the other one of the two points for recording video information on the film.

32. In a system as set forth in claim 30, means operatively coupled to the capstan for controlling the operation of the capstan to control the positions at which the video information is recorded on the film.

33. In a system for transporting from a payout reel to a takeup reel film having sprocket holes and for recording video information on the film in successive frames and successive lines of information within each frame in accordance with video signals having sync signals, the video signals having vertical sync signals for each frame, the combination comprising:

first means for providing a film loop of fixed length;

second means including a capstan engaging the film within the loop for imparting motion to the film; third means responsive to the sprocket holes for providing a control signal representative of the progression and relative position of the sprocket holes; and

fourth means coupled to the second and third means and responsive to the control signal and the video sync signals for controlling the movements of the capstan in accordance with such comparison to obtain a particular rate of progression of the film

within the loop, the fourth means including closed loop servo means for comparing the control signal and the video sync signals to control the movement of the capstan in accordance with such comparison.

34. In a system for transporting from a payout reel to a takeup reel film having sprocket holes and for recording video information on the film in successive frames and successive lines of information within each frame in accordance with video signals having sync signals, the video signals having vertical sync signals for each frame, the combination comprising:

first means for providing a film loop of fixed length;

second means including a capstan engaging the film within the loop for imparting motion to the film; third means responsive to the sprocket holes for providing a control signal representative of the progression and relative position of the sprocket holes; and

fourth means coupled to the second and third means and responsive to the control signal and the video sync signals for controlling the movements of the capstan in accordance with such comparison to obtain a particular rate of progression of the film within the loop, the fourth means including first servo means for comparing the control signal and the video sync signals to provide signals having a variable frequency in accordance with such comparison and the third means including means for providing second control signals representing incremental movements of the capstan between successive sprocket holes in the film and the fourth means including second servo means responsive to the second control signals and the signals of variable frequency from the first servo means to control the movement of the capstan.
